UNITED STATES PATENT OFFICE.

WILLIAM ESTY, OF LACONIA, NEW HAMPSHIRE, ASSIGNOR TO ESTY SPRINKLER COMPANY,
OF LACONIA, NEW HAMPSHIRE, A CORPORATION OF NEW HAMPSHIRE.

AUTOMATIC SPRINKLER FOR STATIONARY FIRE-EXTINGUISHING APPARATUS AND FUSIBLE LINK EMPLOYED THEREWITH.

No. 868,602.

Specification of Letters Patent.

Patented Oct. 15, 1907.

Application filed December 14, 1905. Serial No. 291,777.

To all whom it may concern:

Be it known that I, WILLIAM ESTY, of Laconia, in the county of Belknap and State of New Hampshire, have invented certain new and useful Improvements in 5 Automatic Sprinklers for Stationary Fire-Extinguishing Apparatus and Fusible Links Employed Therewith, of which the following is a specification.

The present invention consists in improvements upon that class of automatic stationary fire extinguishing apparatus which is employed in factories and other buildings for the purpose of automatically flooding the 10 same with water in case of the outbreak of a fire. In such fire extinguishing apparatus, automatic sprinklers are employed, operatively connected with the 15 water supply, which are provided with valves, kept normally closed by suitable releasing devices which are maintained in place by means of a suitable fusible alloy, or solder, the melting point of which is low. In 20 case of the outbreak of a fire, the rise of temperature causes the fusible alloy to melt, whereupon the releasing devices give way, the sprinkler valves are opened and the apartment in which the fire occurs is flooded with water.

The present invention relates to improvements in 25 this type of automatic sprinklers and has for its object the improvement of the same in various respects. In connection with the automatic sprinkler, the present improvements include a fusible link which is capable of general use wherever it is desired to control any 30 opening in case of the outbreak of a fire, whether said opening is closed by a valve, a door, or otherwise.

The improvements are illustrated in the accompanying drawings, in which—

Figure 1, is a front view of one of the improved sprinklers. Fig. 2, is a side view of the same, one of the arms of the sprinkler frame being broken away to show the strut or releasing device. Fig. 3, is a vertical longitudinal section. Figs. 4, and 5, are views of the opposite faces of one of the strut levers. Fig. 6, is a face view of the fusible link. Figs. 7, and 8, are views of opposite faces of one of the link plates.

The improved sprinkler is composed of a frame A, a separable valve B, a distributor C, an adjusting resisting abutment D, and a separable releasing device interposed between the valve and the abutment. The frame A, is adapted to be secured to an appropriate water supply and is equipped at one end with a water passage which is closed by the valve. The frame has a threaded boss by means of which it is secured, to the water supply and has separated arched arms which merge together in line with the water passage where they support the adjustable screw-threaded resisting abutment D. The valve is maintained normally closed by the releasing device. This condition continues un-

til a rise in temperature due to the breaking out of a fire 55 causes the parts of which the releasing device is composed to give way on account of the fusing of the solder or alloy which holds them together, whereupon the valve, being no longer held in place, is forced away by the pressure (air or water) within the water supply 60 pipes, and thus an outlet is opened for the water. The water in passing out encounters the face of the distributor C, and is thereby efficiently distributed throughout the apartment over the area which the particular sprinkler is designed to protect. Generally speaking, this 65 construction and mode of operation is common to sprinklers of this character.

The sprinkler is illustrated in the drawings on the assumption that it is to be attached above the top of a supply pipe and it will be described on this assumption. 70 The sprinkler can, however, be used by suspending it from the supply pipe, in which case the distributor would be at the bottom instead of at the top of the sprinkler.

The present improvements relate to the releasing device and its relation to the valve and resisting abutment. 75

The releasing device comprises two strut levers E, and F; and a fusible link comprising two like link members or plates G, and two like locking levers H. 80

The two strut levers E, F, are substantially alike except that the lever E has a groove a, in which the rounded edge of the other strut lever F, fits and rocks. Either lever may be used uppermost. In the drawings, the lever E, is shown as bearing against the abutment D, while the lever F, is shown as bearing against the valve B, but this arrangement can be reversed. Each lever has a rounded bearing point or ball c, which fits and rocks in a socket d, with which the valve and the abutment are provided. The two strut levers, 85 when in place, have the bearing between them supplied by the groove a, and the edge b, outside of the vertical line between the bearing points c, and c. Consequently, the internal pressure within the water distributing system, acting on the inner face of the valve B, tends to collapse the strut formed by the two levers, as is common in many strut constructions now known in the art. This collapsing strain on the strut levers is resisted by the fusible link. Each strut lever has an outwardly extending elastic or spring arm e. The strut 100 levers are commercially drop-forged from any suitable metal or alloy that has maximum spring efficiency and that is not easily affected by corrosive action, phosphor-bronze spring metal being suitable for this purpose. Each spring arm has at its outer end a notch 105 f, to receive and hold the fusible link.

Each member or plate G, of the fusible link, is a thin plate having a hole g, into which is entered the outer

end of one of the spring arms *e*; a serrated innerface *h*; a longitudinal groove *i* on its outer smooth face; and an aperture *m*, which communicates with the groove *i*, and extends through the body of the plate between 5 the serrated face and the attaching hole *g*. These plates of the fusible link are made of suitable metal which solders readily, such as sheet German silver.

Each locking lever *H*, is composed of suitable material, such as German silver wire. It has a long shank 10 *s*, and bent finger *t*, at an angle to the shank.

The fusible link is assembled by soldering the two serrated faces *h*, together as illustrated in Figs. 2 and 3. These serrated or corrugated faces present ample solder surface for holding the plates together when under the 15 strain to which they are subjected in practice. The two locking levers are then put in place. The shank *s*, of each locking lever is seated within the longitudinal groove *i*, of one of the link plates and its bent finger *t*, is passed into the aperture *m*, in the other link plate. 20 The locking levers are then soldered in place. A compound fusible link is thus made of the two serrated, grooved and apertured plates and of the two bent locking levers soldered together. The solder is indicated in Fig. 2, of the drawings, but is not indicated in 25 Figs. 3, and 6, since it would confuse the illustration of the construction of the assembled fusible link. Owing to this construction of the fusible link, it can be made of ample strength to withstand the strain upon it and at the same time a small thin link can be used. 30 This is of importance because it adds to the sensitivity of the link under the action of heat as well as saving material in the process of manufacture. The less metal that the fire has to heat to the melting point of the solder that holds the parts of the link together, the 35 quicker the solder will fuse and the prompter will be the action of the sprinkler. A fusible link of this construction can be used in any situation where an opening is to be controlled automatically on the outbreak of a fire. It can be used, for example, in the case of 40 fire doors which are to be closed automatically in the case of a fire. In the present case, this construction of the fusible link is shown in connection with the automatic sprinkler. The compound fusible link, when its parts are soldered together as shown in Fig. 6, presents a structure having holes *g*, *g*, at opposite ends, 45 adapted to fit over two spring arms *e*, *e*, of the strut levers *E*, and *F*, and to then fit in the holding notches *f*, *f*.

In assembling the parts of the sprinkler, the two strut levers are put in place between the valve and the 50 resisting abutment with the fusible link in place on the ends of the strut levers; and the adjusting screw abutment is then screwed down until pressure enough is exerted to hold the levers in place and to make the valve tight. This action puts the two spring arms *e*, *e*, 55 of the two strut levers under tension. This tension is resisted by the fusible link. It will be noticed that this tension which is resisted by the fusible link tends to strengthen the strut which, in effect, constitutes a toggle between the valve and the resisting abutment. 60 Consequently, this tension resists the efforts of the internal pressure within the distributing system to collapse the strut. The internal pressure is thus resisted and balanced by the tension on the spring arms. Consequently, no more work is thrown upon the fusible 65 link than if the arms *e*, *e*, were rigid.

In case of the outbreak of a fire, the fusible link disintegrates through the melting of the solder, and very promptly, on account of the small amount of metal in the link; and thereupon, the resilience of the spring 70 arms *e*, *e*, re-acts and instantly throws the strut levers out and away from the valve. The valve is thus left wholly free to be opened by the internal pressure.

I claim—

1. A fusible link composed of two plates and two locking 75 levers soldered together, each plate having a longitudinal groove on one of its faces and an aperture, and each locking lever having a shank fitting in the longitudinal groove of one plate and entering the aperture of the other.

2. A fusible link composed of two plates and two locking 80 levers soldered together; each plate having an attaching hole, serrations on one face, a longitudinal groove on its other face, and an aperture, the serrated faces of the two plates being adjacent each other; and each locking lever having a shank fitting in the longitudinal groove of one 85 plate and entering the aperture of the other.

3. A fusible link composed of two plates and two locking 90 levers soldered together; each plate having serrations on one face, a longitudinal groove on its other face, and an aperture, the serrated faces of the two plates being adjacent each other; and each locking lever having a shank fitting in the longitudinal groove of one plate and entering the aperture of the other.

In witness whereof, I have hereunto signed my name in the presence of two subscribing witnesses.

WILLIAM ESTY.
